UNITED STATES PATENT OFFICE.

HYMAN D. BOWMAN, OF PITTSBURGH, PENNSYLVANIA.

FLUID-MIXING DEVICE.

Application filed May 6, 1927. Serial No. 189,300.

This invention relates to fluid mixing devices and more in particular to fluid mixing devices to be used in connection with internal combustion engines of the type used especially 5 on automobiles and the like.

One of the primary objects of this invention is to provide a fuel mixing device which is operated and regulated automatically by the suction created by the movements of the pistons of an engine in the intake manifold and whereby properly gauged amounts of gasoline, water, air and vapor may be used to produce the most economical operation of the engine at all kinds of speeds. Another object 15 is to eliminate to a great extent the formation of carbon deposits in the cylinders, due to the imperfect combustion of the fuel. A further object is to produce artificially operating conditions for the engine akin to those prevailing 20 in damp weather, which conditions, as is well known, are most favorable for the good operation of the engine. Still another object is to provide a fuel mixing device which is relatively simple in construction, easily 25 adjusted and which may be applied with little trouble and alterations on old engines as well as new ones. Additional features and advantages of this invention will appear from the following description considered in connection 30 with the accompanying drawing forming a part of this application, and in which:

Fig. 1 is a longitudinal section through one type of mixing device built in accordance with my invention, and connected to various accessories, for a purpose to be explained later.

Fig. 2 is a top view of Fig. 1.

Fig. 3 is a longitudinal section showing a modified mixing device.

40 Fig. 4 is a fragmentary view showing an alternative method of connecting various supply pipes to the mixing device.

Fig. 5 is a longitudinal section through another modification of the mixing device.

45 Fig. 6 is a top plan view taken on line 6-6 in Fig. 5.

Fig. 7 is a fragmentary view showing one method of connecting the mixing device with the intake manifold of an internal combustion engine.

50 Fig. 8 is a fragmentary view showing a modification of the connection shown in Fig. 7.

Fig. 9 is a rear elevation of the fluid discharge element shown in Fig. 8.

Fig. 10 is a longitudinal section illustrating still another alternative construction of my mixing device.

Figs. 11 and 12 are fragmentary views showing two alternative arrangements for 60 pre-heating mixed fluids before directing them into the intake manifold.

A fluid mixing valve of the construction shown in Figs. 1 and 2 consists of the body 1 comprising the cylinder housing or suction chamber 2, the atmospheric chamber 3, the mixing chamber 4 and the fuel-chamber 5 all properly aligned and secured by means of two sets of screws 6 and 7. Movable within the cylinder is a control-piston 8 comprising a 70 disc-member 9 in the grooved circumference of which is laid the annular coil spring 10 which exerts a constant outward pressure on the piston packing 11 held in place by the guide washer 12 and the nut 13 screwed on the upper threaded portion of the piston rod 14. The piston is acted upon by a coil spring 15 the tension of which may be adjusted by means of a threaded bushing 16 which bears upon the spring-cap 17 placed at the upper 75 end of said spring. A lock-nut 18 holds the bushing in the adjusted position. The upward travel of the piston may be regulated by means of the adjusting screw 19 positioned in the bushing in line with the piston-rod and 80 locked by the lock-nut 20.

The piston-rod 14 extends down into the fuel-chamber 5 and is guided through the partition 21 which separates the air-chamber from the mixing chamber by a stuffing box 90 22. The lower end of the piston-rod is slightly reduced in diameter and threaded to receive the closing-valve 23 and the frusto-conical controlling valve 24, the former valve being preferably spherical, although other forms of valves may be used. These two valves are adapted to engage respectively the upper and the lower ends of the valve-port 25 drilled in the partition 26 which separates the mixing chamber and the fuel chamber. In 95 the bottom of the latter is drilled through the aperture 27 and in the thickened portion 28 of said bottom is produced a duct 29 which is directed radially to the outer periphery of the device and into which is screwed the discharge line 30 which is connected into the intake manifold at a point intermediate the engine and the usual carburetor (not shown) found on internal combustion engines for 100 self-propelled vehicles. At the lower end, the 105

device has an outwardly threaded shank 31 which is screwed into a suitably tapped aperture 32 provided in the exhaust manifold 33 and whereby the mixing device may be fastened on the latter. The aperture 27 and the duct 29 extend right through the shank and are connected to the U-shaped heating element or tube 34 which protrudes, of course, into the exhaust manifold.

10 The various component fluids of the fuel-mixture are led by suitable pipes into the mixing chamber 4. In Figs. 1 and 2 I have shown three fluid supply pipes 35, 36 and 37 which are intended to carry respectively 15 gasoline, water and air in the desired proportions adjustable by means of needle-point valves 38 as shown for the gasoline supply tube. Gasoline may be piped from the storage tank or from the vacuum tank; and 20 water from the cooling system of an automobile, whereas air may be drawn directly from the atmosphere or from the crank-case of the engine, in which latter case the gasoline fumes escaping into the crank-case will 25 be recovered to produce useful work. However, if desired, gasoline and water could be obtained from special storage tanks made for the purpose.

The suction chamber 2 communicates with 30 the discharge tube 30 through a duct 39 which is provided in one side of the body and the atmospheric chamber 3 is at all times in communication with the atmosphere through the port-holes 40 drilled through the wall of said 35 chamber.

In the several supply-pipes may be installed the shut-off valve 41, the ball check-valve 42 and the thermostatic-valve 43, the purpose of the latter being to cut off the supply of fluid until the engine is well heated. 40 This thermostatic valve is mounted by means of screws 44 on the exhaust manifold 33 and consists of the valve-body 45, the valve-disc 46, the valve stem 47 the lower end of which 45 is fastened to the thermostatic strip 48 held very close to the exhaust manifold so as to be influenced by its temperature. When the engine is running, the exhaust manifold is heated and the strip 48 warped up, so that the 50 valve-disc opens up; whereas when the engine is stopped, the exhaust manifold cools down and said strip assumes the flat shape shown in dot and dash lines whereby the valve is shut. The closing of this valve is 55 additionally assisted by the coil spring 49. The check-valve prevents any heated fuel-mixture from flowing backwards into the supply line. This last named valve as well as the hand adjusted shut-off valve are of 60 commercial type and their construction will be readily understood. To prevent any foreign matter entering and clogging the mixing-device, a wire screen 50 may be inserted in the body of the shut-off valve, being 65 held in place by the special pipe fitting 51.

If desired, the water and air supply pipe may be connected to the gasoline pipe just ahead of the shut-off valve, to reduce the number of valves used. This is done by placing in the supply-pipe 35 the cross-shaped pipe-fitting 52 to which the various supply-pipes are connected, as suggested in Fig. 4.

The modified construction shown in Fig. 3 differs principally from the one just described in that a flexible diaphragm 53 has been substituted for the control-piston 8. The body of this valve is also built up of four sections which form the suction-chamber 54, the atmospheric chamber 55, the mixing-chamber 56 and the fuel-chamber 57, the bottom of which has a threaded shank 58 whereby the device is screwed onto the exhaust-manifold 33. A spring 59 presses on the top side of the diaphragm and the vertical lift of the latter is defined by the adjusting screw 60 which lies in axial alignment with a diaphragm-rod 61 upon which are threaded for longitudinal adjustment the closing valve 23 and the controlling valve 24. The compression in spring 59 is regulated by means of the bushing 62 in which is provided a stuffing box 63 to prevent leaks. Various other parts whose purpose and design have already been described in the first mentioned construction, are identified by the same reference numbers.

In the modification shown in Figs. 5 and 6, the formerly called mixing-chamber has been divided by radial partitions 64 into as many tight compartments 65 as there are 100 component fluids in the fuel-mixture, three in the present embodiment, namely gasoline, water and air, and the fuel-chamber 66 now functions also as a mixing-chamber. Each fluid has its own closing valve 23 and controlling valve 24 which are vertically adjustable on their corresponding valve-rods 67 all of which are mounted on a common piston 68 of substantially identical construction as the one in Fig. 1, except that the piston-rod 69 105 serves now only as a guide for the piston by traveling within suitable registering apertures 70 drilled in central hubs provided in the partitions 71 and 72. Stuffing boxes 22 are also shown for the valve-rods 67. Other parts of previously described purpose are defined by formerly used reference numbers.

Fig. 10 represents another alternative construction of the fuel-mixing device, in which the closing-valve 23 and the control-valve 24 are actuated by individual pistons moving in separate bodies, having a common base 73. In the latter are provided the pockets 74 and 75 which form the bottom portion of the so-called fuel-chambers and which are 110 connected together by a duct 76. The pocket 74 is closed at the bottom, whereas the pocket 75 has the threaded shank 31 and the heating element 34, which reaches into the exhaust manifold 33. Suitably drilled lugs 77 and 115

a U-bolt 78 may be used, if desired, to additionally secure the device on the exhaust manifold 33.

Instead of introducing the fuel heating element into the exhaust manifold, it may be found preferable, especially on old engines, to heat the fuel from the outside of said manifold. In Fig. 11 I have shown a modified fuel-chamber 79 which has a suitably curved bottom 79^a which fits the top of the manifold. The heat of the latter will be communicated to the rather thin bottom of the chamber, thus heating the fuel mixture therein. In this case, the device would be secured by means of a U-bolt 80 engaging suitably drilled lugs 80^a.

Another way of heating the fuel mixture is suggested in Fig. 12 wherein the heating element consists of a tube 81 wound around the exhaust manifold and connected to the fuel-chamber in a manner stated heretofore. Two U-bolts 82 are shown for fastening the device on the manifold. Suitably curved bearing ribs 83 have been provided at the bottom of the fuel-chamber to support the latter the required distance above the manifold to provide room for the heating element.

As already stated, the heated fuel-mixture is led into the intake manifold by means of the discharge line 30. Various constructions for introducing this fuel may be resorted to. In Fig. 7 an elbow fitting 84 is screwed into the intake-manifold 85 and has a perforated extension 86 through which the fuel is discharged in a multitude of small sprays into said manifold.

The construction illustrated in Figs. 8 and 9 comprises the elbow fitting 87 screwed into a threaded plug 88 in which is screwed a tube 89 having at its lower end a cage-like housing 90 in which is mounted a helical impeller 91 which is actuated by the suction draft within the intake manifold. The fuel mixture coming from the discharge line 30 is discharged through the aperture 92 against the fan and dispersed into small streams by passing through a fine mesh-screen 93 provided around and in front of the housing 90. The purpose of the large plug 88 is, of course, to permit the insertion of the housing and its tube into the intake manifold.

Operation.

It is well known, that the suction as read on a vacuum gauge in the intake manifold of an internal combustion engine is greatest when the throttle valve is closed and least when said valve is full open. On account of the discharge line 30 being connected to the intake manifold at a point between the throttle valve and the engine cylinders, it follows that substantially the same vacuum pressure will prevail in the heating element 34 and also in the suction chamber 2, because

of the duct 39. When the engine is started, for instance, the throttle valve is nearly closed and the partial vacuum created in the suction-chamber 2 (Fig. 1) will enable the atmospheric pressure in the atmospheric-chamber 3 to overcome the pressure of the coil-spring 15 and force the piston and connected controlling-valve 24 up, and the latter may, according to its adjustment on the piston-rod 14, fully close the valve-port 14, or just leave it partly open so that a small amount of the fuel mixture in the mixing chamber may be sucked into the heating element and thence into the engine. When the engine is not running, there is, of course, no suction in the intake manifold or in the suction-chamber 2 and therefore, any flow of the fluid-mixture is prevented by the closing-valve 23 which is then forced on its seat by the coil-spring 15. On the other hand, when the engine is running at full speed and the throttle valve is opened full, or nearly full, the vacuum pressure in the intake manifold is reduced accordingly. The difference in pressure between the suction-chamber 2 and the atmospheric-chamber 3 becomes less so that the piston will be lifted a lesser amount, and the control valve will allow a greater amount of the fuel mixture to flow into the discharge line 30. By properly adjusting the coil-spring 15 and the control-valve 24 the correct amount of fuel mixture may be supplied to suit different operating conditions of the engine.

I am aware of the fact that various types of fuel-mixing devices have been tried or patented but, so far as is known to me, these devices operate practically the reverse of my device, that is to say the fuel mixture introduced is least when the throttle valve is opened the most and vice-versa.

Although the operation of my device has been explained in connection with a carburetor, the former may be used alone in which case it would be called upon to supply the whole amount of fuel, instead of serving as an auxiliary supplier of fuel.

It is thought that the above description of the operation of the mixing device shown in Figs. 1 and 2 will suffice to explain the fundamental principle upon which the other alternative constructions are also based, and that further comment on this subject will not be required by those versed in the art.

As will be understood, as suggested herein, there may be slight changes made in the construction and arrangement of the details of my invention without departing from the field and scope of the same, and I intend to include all such variations, as fall within the scope of the appended claims, in this application in which the preferred forms only of my invention are disclosed.

I claim:

1. In a fuel mixing device, for internal

- combustion engines of the character described, having a suction chamber, an atmospheric chamber, a mixing chamber and a fuel chamber communicating therewith,
- 5 the combination of a plurality of lines for conducting the component fluids of said fuel into said mixing chamber; a heating element in communication with said fuel chamber and with the intake manifold of said engine;
- 10 said intake manifold being in communication with said suction chamber; a member movable within the suction chamber; means for exerting a downward pressure on said movable member; a valve-stem positioned
- 15 on said movable member and a valve on said valve-stem for cutting off the communication between said mixing chamber and fuel chamber when said engine is at a stand still.
2. In a fuel mixing device for internal combustion engines of the character described, having a suction chamber, an atmospheric chamber, a mixing chamber and a fuel chamber communicating therewith, the combination of a plurality of lines for conducting
- 25 the component fluids of said fuel into said mixing chamber; a heating element in communication with said fuel chamber and with the intake manifold of said engine; said intake manifold being in communication with
- 30 said suction chamber; a member movable within the suction chamber; means for exerting a downward pressure on said movable member; a valve-stem positioned on said movable member, a valve on said valve-stem for cutting off the communication between said mixing chamber and fuel chamber when said engine is at a stand-still and a control-valve also mounted on said stem for regulating the supply of fuel to said intake
- 35 manifold, according to the pressure prevailing in said suction chamber.
3. In a fuel mixing device for an internal combustion engine of the character described having a suction chamber, a separate atmospheric chamber, a separate mixing chamber and a fuel chamber communicating with the latter, all of said chambers being mounted in superposed axial alignment to form a unitary body, the combination of a plurality of
- 40 lines for conducting the component fluids of said fuel into said mixing chamber; a tubular heating-element in communication with said fuel chamber and with the intake manifold of said engine, and means actuated by the
- 45 fluid pressure in said intake manifold for controlling the amount of mixed fuel supplied to said manifold.
4. In a fuel mixing device for an internal combustion engine of the character described
- 50 having a suction chamber, a separate atmospheric chamber, a separate mixing chamber and a fuel chamber communicating with the latter, all of said chambers being mounted in superposed axial alignment to form a
- 55 unitary body, the combination of a plurality

of lines for conducting the component fluids of said fuel into said mixing chamber; a tubular heating-element in communication with said fuel chamber and with the intake manifold of said engine; means actuated by the fluid pressure in said intake manifold for controlling the amount of mixed fuel supplied to said manifold, and spring actuated means for cutting off the supply of the mixed fuel to said engine when inoperative.

5. In a fuel mixing device for an internal combustion engine of the character described, having a suction chamber, an atmospheric chamber, a mixing chamber and a fuel chamber communicating therewith through a port, the combination of a plurality of lines for conducting the component fluids of said fuel into said mixing chamber; a heating element in communication with said fuel chamber and with the intake manifold of said engine, said intake manifold being in communication with said suction chamber; a member movable within the suction chamber; means for exerting a downward pressure on said movable member; a valve-stem positioned on said movable member and a valve mounted on said stem and longitudinally adjustable thereon for cutting off the communication between said mixing chamber and fuel chamber when said engine is inoperative.

6. In a fuel mixing device for an internal combustion engine of the character described, having a suction chamber, an atmospheric chamber, a mixing chamber and a fuel chamber communicating therewith through a port, the combination of a plurality of lines for conducting the component fluids of said fuel into said mixing chamber; a heating element in communication with said fuel chamber and with the intake manifold of said engine, said intake manifold being in communication with said suction chamber; a member movable within the suction chamber; means for exerting a downward pressure on said movable member; a valve-stem positioned on the movable member and having a threaded portion extending within said mixing and fuel chambers and engaging said port; a valve adjustable on said threaded portion for cutting off the communication between the last two mentioned chambers, and a control-valve also mounted for longitudinal adjustment on said threaded portion for regulating the supply of fuel to said intake manifold according to the pressure prevailing in said suction chamber.

7. In a fuel mixing device for an internal combustion engine of the character described, having a suction chamber, an atmospheric chamber, a mixing chamber and a fuel chamber communicating therewith through a port, the combination of a plurality of lines for conducting the component fluids of said fuel into said mixing chamber; a heating element in communication with said fuel

chamber and with the intake manifold of said engine, said intake manifold being in communication with said suction chamber; a member movable within the suction chamber; adjustable resilient means for exerting a downward pressure on said movable member; a valve-stem positioned on the movable member and having a threaded portion extending within said mixing and fuel chambers and engaging said port; a valve adjustable on said threaded portion for cutting off

the communication between the two last mentioned chambers, and a frusto-conical control valve mounted for longitudinal adjustment on said threaded portion and adapted to gradually restrict the passage area of said port for regulating the supply of fuel to said intake manifold according to the pressure prevailing in said suction chamber.

15 In testimony whereof I affix my signature.

HYMAN D. BOWMAN.
